[57] CLAIM

The ornamental design of a golf putter, as shown and described.

DESCRIPTION

FIG. 1 is a front elevational view of a golf putter showing my new design;

FIG. 2 is a rear elevation thereof;

FIG. 3 is a right side elevational view thereof, the undisclosed opposite side being a mirror image;

FIG. 4 is a top plan view thereof;

FIG. 5 is a bottom plan view thereof; and,

FIG. 6 is an enlarged perspective view thereof.

The broken line showing of a fragmented shaft is for illustrative purposes only and forms no part of the claimed design.
